F i g. 1

F i g. 2

FIGURE 1 is a perspective view of a telephone booth showing the front, one side and the top thereof, showing our new design.

FIGURE 2 is another perspective view showing the other side and the rear thereof with the telephone and telephone book shown in broken lines for illustrative purpose only.

The dominant features of our design reside in the portions shown in full lines.

We claim:

The ornamental design for a telephone booth, substantially as shown and described.
